UNITED STATES PATENT OFFICE

2,539,622

TYPEWRITING MACHINE WITH A SECOND RIBBON AND MEANS FOR GUIDING THE SAME

Paul Hegnauer, Zurich, Switzerland, assignor to
Ruf-Buchhaltung Aktiengesellschaft, Zurich,
Switzerland

Application July 13, 1946, Serial No. 683,545
In Germany June 5, 1941

**Section 1, Public Law 690, August 8, 1946
Patent expires June 5, 1961**

2 Claims. (Cl. 197—153)

1

The invention relates to a typewriter having a carriage with a platen and a ribbon feed mechanism of known construction.

The invention relates more particularly to typewriters of the said type adapted for the use of bookkeeping having a device to write simultaneously on a plurality of sheets of which one is a ground sheet or record sheet and two others are loose or account sheets which are frequently to be replaced.

The main object of the invention consists in the provision of a device of the kind aforesaid in which the two account sheets are both written upon by means of ribbons.

In the accompanying drawing an embodiment of the invention is shown by way of an example in a diagrammatical manner.

Fig. 1 is a front elevation of the device and

Fig. 2 is a side elevation thereof.

Fig. 3 is a section showing the guides for the sheets and the ribbons.

Fig. 4 shows the device in a perspective view.

In the drawings W denotes the platen which is rotatably mounted in the carriage 2 of a type-writer in the well known manner. Above the platen W and in side walls of the carriage 2 a shaft 1 is rockingly mounted on which a frame 2' is fastened. In the frame 2' two guide-ways are arranged comprising a division wall 5 and two side walls running parallel to each other and to said division wall 5. The walls 3, 4 and 5 stand upright, they are slidably arranged on a bar 12 of the frame 2' and form channels or guide-ways 15, 16 one on each side of the division wall 5. The guide-ways are open at the top and at the lower end, and the walls 3, 4 and 5 end in front of the platen W above the ribbons F and 8. By the guide-ways 15 and 16 the sheets J₁ and J₂ are fed by their own weight into their position between the ribbons F and 8; and between the ribbon 8 and a carbon sheet K running above the paper record sheet G over the platen W. The ribbon 8 projects with its upper edge in a groove 11 of the division wall 5. The ribbon 8 runs in guides 9, 18, and follows the walls 3, 4, 5 when the latter swing about shaft 1 over spools 6, 7 rotatably mounted on the carriage 2.

In writing, the sheet J₁ and the sheet J₂ are written upon by the use of the ribbons F and **8**. Simultaneously the sheet G is written on by making use of the carbon sheet K. The latter is fed in the well known manner together with sheet G by turning step by step the platen W.

By inserting the sheets J_1 and J_2 into the guides
ways 15 and 16 the sheets pass automatically to
their proper position with reference to the carbon
ribbons E, F and carbon sheet K.

If only one of the sheets J_1 or J_2 is to be written upon the said sheet will be inserted into the guide way 15. The sheet is written upon by 60

2

making use of the ribbon F while the ribbon G is used to write on the sheet G, the ribbon G being guided in the groove H.

What I wish to secure by U. S. Letters Patent is:

1. In a typewriting machine having a carriage in which a platen is rotatably mounted, a shaft rockingly mounted in said carriage above said platen, a frame secured to said shaft, said frame being provided with two guideways for the reception of record sheets and for guiding them to a place in front of said platen, said guideways being formed by a central division wall and two side walls spaced from opposite sides of said division wall and arranged parallel thereto, said guideways being open at their top and their lower ends, means for guiding a ribbon in front of said platen, means for guiding a second ribbon between said first named ribbon and said platen, the lower end of said central division wall having a longitudinal groove for receiving one longitudinal edge of said second ribbon and for guiding the latter in spaced relation behind said first named ribbon.
  2. In a typewriting machine having a carriage in which a platen is rotatably mounted, a shaft rockingly mounted in said carriage above said platen, a frame secured to said shaft, said frame being provided with two guideways for the reception of record sheets and for guiding them to a place in front of said platen, said guideways being formed by a central division wall and two side walls spaced from opposite sides of said division wall and arranged parallel thereto, said guideways being open at their top and their lower ends, means for guiding a ribbon in front of said platen, and in front of a record sheet which is discharged from the lower end of one of said guideways, and a longitudinal groove in the lower edge portion of said central division wall for guiding a second ribbon in spaced relation behind the first named ribbon and behind the first named record sheet, said second ribbon being arranged to lie in front of the record sheet which is discharged from the lower end of the other guideway.

PAUL HEGNAUER.
